(57) **CLAIM**

The ornamental design for a UCL luminaire, as shown and described herein.

DESCRIPTION

FIG. 1 is a bottom right side perspective view illustrating the UCL luminaire in accordance with the first embodiment of my new design;

FIG. 2 is a left side elevation view of the luminaire shown in FIG. 1;

FIG. 3 is a top plan view of the luminaire shown in FIG. 1; FIG. 4 is a bottom plan view of the luminaire shown in FIG. 1;

FIG. 5 is a left side elevation view illustrating the UCL luminaire in accordance with the second embodiment of my new design;

FIG. 6 is a right side elevation view of the luminaire shown in FIG. 5;

FIG. 7 is a front side elevation view of the luminaire shown in FIG. 5;

FIG. 8 is a rear side elevation view of the luminaire shown in FIG. 5;

FIG. 9 is a left side elevation view illustrating the UCL luminaire in accordance with the third embodiment of my new design;

FIG. 10 is a right side elevation view of the luminaire shown in FIG. 9;

FIG. 11 is a front side elevation view of the luminaire shown in FIG. 9; and,

FIG. 12 is a rear side elevation view of the luminaire shown in FIG. 9.
